UNITED STATES PATENT OFFICE.

ALBERT G. FRUHLING, OF LOS ANGELES, CALIFORNIA.

SCREENED FRAME FOR VENTILATING-WINDOWS.

1,091,743.

Specification of Letters Patent. Patented Mar. 31, 1914.

Application filed April 22, 1913. Serial No. 762,786.

To all whom it may concern:

Be it known that I, ALBERT G. FRUHLING, a citizen of the United States, and residing in the city of Los Angeles, county of Los Angeles, and State of California, have invented a new and useful Improvement in Screened Frames for Ventilating-Windows, of which the following is a specification.

This invention relates to screen frames for windows, and especially to ventilating windows placed in large windows built up of separable sections, and the principal object of the invention is to provide a screen that will not interfere with the efficient tilting of one of the sections.

It is a further object to provide a window screen which can be readily removed from the frame without disturbing or interfering with the action of the tilting section.

In the drawings accompanying this specification and forming therewith the application for Letters Patent: Figure 1 is a front elevation of a window having the ventilating section showing the screen applied thereto. Fig. 2 is an enlarged rear elevation similar to Fig. 1 clearly showing the locking means for securing the window in closed position. Fig. 3 is an end elevation of Fig. 2 showing the window sash tilted in relation to its frame and the screen mounted thereon. Fig. 4 is an enlarged section on the line 4-4 of Fig. 2 viewed in the direction indicated by the arrows.

Heretofore in the operation of ventilating windows in large sectional window sash, difficulty has been experienced in properly screening the same where other entrances and exits are properly screened, and this invention aims to overcome the above difficulties by providing a ventilating window with screens so that when the window is open the above area will be efficiently covered with screen and prevent the ingress of undesirable insects.

More specifically in the drawings, 5 designates a window built up in the common sectional form, in which is located the ventilating window casing 6, within which is pivotally mounted the sash 7. This sash 7 is provided with trunnions 8 which are adapted to slide into the inclined grooved frame 9 in the sides of the casing 6, acting as a bearing for the trunnions, the upper portion of the casing being preferably provided with a latch strike 10 with which the pivoted

latch 11 is adapted to engage to secure the window in closed position.

To provide a suitable stop for the window when it is unlatched and the upper portion swings away from the latch strike, 60 the metal flange of the upper portion of the frame is upset on its front face to form the flap 12, against which the outer face of the sash abuts and holds the sash in horizontal position, as clearly shown in Figs. 3 and 65 4. The portion of the metal upset, as described, is a portion of a flange 14 which on the exterior face extends down to this point. A similar flange 15 is formed on the inner face of the casing, which also acts as 70 a stop, and a tight fit for the sash when it is in the closed position. Secured to these vertical flanges are a plurality of clips 16, those of the upper section act with the upturned flap 12 to form an efficient support for the 75 screen frame 17 inclosing the screen 18. The lower edge of the frame 17 terminating close to the sash 7 and the glass contained therein, so that the opening therebetween is not of sufficient height to permit the entrance of 80 insects.

The clips 16 on the inner flange 15 together with flanges 19 on the lower section 20 of the casing, form efficient supporting clips for the inner screen frame 21, which is 85 also provided with a screen 22, the parts being so arranged that the upper edge of the screen 21 abuts against the inner face of the swinging portion of the sash when the latter is in its horizontal or open position. 90

When it is not desired to have the screen in the window, the same may be readily removed by slipping the vertical part of the frame, the outer one with the window in open position, and the inner, necessarily 95 when the window is closed.

The screen frames 17 and 21 are preferably formed of metal, as are all of the other parts, constituting a fire proof structure, and are preferably built of narrow flat channelled 100 metal, within which the edges of the wire screen are efficiently clamped.

What I claim is:

1. A window screen construction comprising a window casing having side and end 105 walls, the side walls thereof being provided with inclined slots and oppositely disposed flanges adapted to engage a window sash pivotally mounted in the slots in the side of said casing, a plurality of vertically dis- 110

posed clips secured to said casing adjacent the upper flanges of said window casing, said flanges having an upset end adapted to form a support for a screen, a plurality of 5 vertically and horizontally disposed clips secured to the edges of the lower section of said casing on its inner face, and screened frames oppositely disposed on said casing, the upper of said screens being supported 10 upon said upturned flanges and secured by said vertically disposed clips, and the lower of said screens being secured by the vertically and horizontally disposed clips on the flanges on the inner face of the casing, 15 whereby said window sash may be pivotally swung and the exposed area efficiently screened.

2. A screen frame construction for ventilating windows, comprising a stationary 20 frame adapted to be secured in a window opening, a window pivotally mounted in said frame to form a closure for the opening,

a screen mounted on the outer face of the upper half of said frame and disposed in parallel relation therewith, a second screen 25 mounted on the inner face of the lower half of said frame and disposed in parallel relation therewith, the upper edge of the lower screen and the lower edge of the upper screen each terminating at one side of the 30 pivotal points of said window, the space between the two said screen edges approximately corresponding to the thickness of the pivoted window, whereby when the window is swung from a vertical to a horizontal position the space between the adjacent edges of said screens will be substantially closed. 35

In witness that I claim the foregoing I have hereunto subscribed my name this 12th day of April, 1913.

ALBERT G. FRUHLING.
